UNITED STATES PATENT OFFICE

EDWIN W. SCHULTZ AND FRANK D. BANHAM, OF PALO ALTO, CALIFORNIA; SAID
BANHAM ASSIGNOR TO SAID SCHULTZ

GRINDER AND DISINTEGRATOR

Application filed May 4, 1929. Serial No. 360,372.

This invention relates to a machine for pulverizing, grinding or disintegrating solid or semi-solid materials such as those employed in pharmaceutical, biological and medical work. The apparatus is particularly applicable to all work which is ordinarily performed by hand with a mortar and pestle.

In the disintegration of fibrous materials such as herbs, grasses and tissues for pharmaceutical or biological work, it has been necessary to grind or disintegrate the materials by hand in a mortar. Materials of the character stated are disintegrated or reduced to a fine state of division with great difficulty, and often require manual grinding for periods of several hours. This method of reducing materials to a fine state of division is not only tiresome, but time consuming.

It is an object of this invention to disclose and provide a device which will automatically grind and disintegrate materials to a fine state of division, quickly and automatically.

It is another object of this invention to disclose and provide a mechanism which will automatically subject material being ground or disintegrated to conditions of pressure and manipulation comparable to those employed when such materials are manually disintegrated or ground.

Another object is to disclose and provide a compact, portable, grinding and disintegrating apparatus capable of reducing fibrous and muscular tissues to a state of fine division.

Another object is to disclose and provide a grinding and disintegrating apparatus in which the grinding elements are yieldably urged together.

Other objects, uses and advantages of this invention will become apparent from the following detailed description of two preferred forms of the invention. In describing the preferred forms of the apparatus embraced by this invention, reference will be had to the appended drawings, in which:

Fig. 1 is a plan view of one form of apparatus, the cover or hood being removed.

Fig. 2 is a side elevation, partly broken away, of the apparatus shown in Fig. 1.

Fig. 3 is a plan view of a modified form of apparatus.

Fig. 4 is a side elevation of the apparatus shown in Fig. 3.

Referring to Fig. 1, the apparatus may include a base 1, upon which a pedestal 2 may be mounted. The entire apparatus may be enclosed within a hood 3 resting upon a partition or floor 4 supported from the base 1 on suitable pillars 5. The floor 4 may separate a driving means from the grinding or disintegrating chamber, the hood 3 permitting the grinding or disintegration to be carried out under sterile conditions or in a suitable oxidizing or non-oxidizing atmosphere.

A vertical shaft 6 may be journaled in the pedestal 2, suitable thrust bearings being provided at 7 on which the shaft 6 may be supported. The shaft 6 preferably extends upwardly into the grinding and disintegrating chamber and above the floor 4, and bears at its upper end a driving disc 8 provided with a plurality of eccentrically disposed apertures 9.

A worm wheel 10 is preferably mounted upon the shaft 6, and a worm 11 mounted upon a horizontal shaft 12 positioned in operable contact with the worm wheel 10 so as to impart motion to the worm wheel 10 and shaft 6. As shown in Figs. 1 and 2, the worm 11 and the horizontal shaft 12 may be directly driven by an electric motor 13 attached to the base 1.

Preferably, means for causing a relative motion between a receptacle in which the materials to be ground are contained and a grinding means are provided. Such means may take the form illustrated in Figs. 1 and 2, in which a platen 14 is preferably movably positioned above the disc 8, and operably connected thereto by means of a pin 15 positioned in one of said eccentric apertures 9 and journaled in an aperture formed in the platen 14. The platen 14 may be provided with a bifurcated end provided with a guide 16, said guide or slot 16 cooperating with a fixed pin 17 attached to the pedestal 2 or to some other immovable portion of the apparatus.

Friction reducing means may be positioned between the disc 8 and the platen 14. For example, rollers 18 may be rotatably journaled in the disc 8, the rollers 18 extending

above the top surface of the disc 8 and contacting with the lower surface of the platen 14. Instead of the rollers 18, ball or other suitable bearings may be introduced between the disc 8 and the platen 14.

5 A receptacle for the materials to be ground may be positioned upon the platen 14 and held immovably thereon. For example, the mortar 19 may be retained between upwardly 10 extending fingers 20 attached to the platen 14.

Means for adjustably positioning a grinding means with respect to the receptacle may be provided, said means including, for example, a vertical rod 21 on which a clamp 22 15 may be adjustably positioned. The clamp 22 may be provided with an elastic extension or connecting member 23, bearing at its outer end a clamp 24 provided with a tightening screw 25 adapted to grip a pestle 26.

20 The above mechanism permits the disintegration and reduction to a state of fine division of cellulosic fibrous and other difficultly disintegrated materials. The driving disc 8 imparts an eccentric motion to the 25 platen 14 and to the receptacle or mortar 19 held thereon. The grinding means or pestle 26 may be adjustably positioned so as to contact operably with the material within the receptacle 19 by adjusting the clamps 24 and 30 22. Furthermore, the pestle 26 is yieldably urged toward the grinding surface of the receptacle 19 by the flexible or elastic arm 23 which may be made of spring steel, rubber, 35 composition or an assemblage of wood, springs, etc.

The eccentricity of the relative movement between the pestle 26 and the receptacle 19 may be adjustably varied by changing the 40 location of the pin 15 and by changing the location of the pin 17 with respect to the vertical axis of the shaft 6.

45 The receptacle 19 does not move in a circle, but instead moves through an elliptical or eccentric course, the oscillation depending upon the location of the pin 17 and the pin 15, as above described. In this manner the relative movement of the pestle 26 and the receptacle or mortar 19 may be easily changed and adjusted, depending upon the character 50 of the material being ground or disintegrated and upon the size of the mortar used.

A modified form of device is shown in Figs. 5 and 4. In the modified form of device the pedestal 2 bears a vertical shaft 6, upon which the worm wheel 10 is mounted and which is driven by the worm gear 11 upon the horizontal shaft 12. The shaft 6 also carries the disc 8 which is also provided with a plurality of eccentrically spaced apertures 9. The pin 60 15 mounted in one of said apertures 9 of the disc 8 may be journaled in a platen 27 provided with a longitudinal guide 28, which cooperates with a fixed pin 17 attached to the pedestal 2.

65 A flexible elastic or yielding arm 29 may be

attached to that end of the platen 27 opposed to the end in which the pin 15 is journaled, the member 29 terminating in a clamp 24 adapted to grip and support a grinding means or pestle 26.

70 The grinding receptacle or mortar 19 may be clamped into position upon the base 1 or be held in place by means of fingers 30 extending upwardly from the base 1. The fingers 30 may be rubber covered so as to prevent the mortar 19 from slipping.

75 The modified form shown in Figs. 3 and 4 also permits a relative movement between the platen or receptacle in which the material to be ground or disintegrated is contained and the grinding means, and allows the grinding means to be yieldingly urged toward the grinding surfaces.

80 An apparatus of the character described above has been found to be very effective for use in grinding or disintegrating cellulosic, fibrous or muscular materials. For example, tissues containing fibrous corpuscles may be finely ground in a relatively short period of time under sterile conditions, by employing 85 sterilized mortars and pestles and operating these under a hood or cover of the character shown in Fig. 2. If desired, a glass door or cover 31 may be provided in the top of the hood 3 so as to facilitate inspection and 90 adjustment of the grinder and of the material being treated.

95 The apparatus is very compact, portable and readily adjusted and cleaned.

100 It is to be understood that the invention is not limited to the particular combination and arrangement of elements described in detail hereinabove and shown in considerable detail in the drawings. Broadly considered the invention relates to means for producing an oscillatory motion between grinding means and means for yieldably or flexibly supporting a grinding means. The invention includes all such changes and modifications as come within the scope of the appended claims.

105 We claim:

110 1. In a grinding and disintegrating apparatus the combination of a driving disc, means for driving said disc, a platen movably positioned above said disc, a pin eccentrically mounted in said disc and journaled in said platen, being provided with a guide adapted to slidably cooperate with a fixed pin; a substantially stationary grinding member, and a complementary grinding member in operative contact with said first grinding member and actuated by said platen.

115 2. In a grinding and disintegrating apparatus the combination of a driving disc, means for driving said disc, a platen movably positioned above said disc, an eccentric driving connection between said disc and platen, said platen being provided with a guide adapted to slidably cooperate with a fixed pin, a receptacle carried by said platen, and means 120

115

120

for operatively positioning a grinding means with relation to said receptacle, including means for yieldably urging said grinding means in contact with said receptacle.

5 3. In a grinding and disintegrating apparatus the combination of a driving disc, means for driving said disc, a platen movably positioned above said disc, an eccentric driving connection between said disc and platen, said platen being provided with a guide adapted to slidably cooperate with a fixed pin, a receptacle carried by said platen, and means for operatively positioning a grinding means with relation to said receptacle, including

15 means for causing said grinding means to exert a predetermined pressure upon said receptacle.

4. In a grinding and disintegrating apparatus the combination of a pedestal, a vertical shaft journaled in said pedestal, a driving disc carried on the upper end of said shaft, means for driving said shaft, a platen movably positioned above said disc, said platen being provided with a guide adapted to slidably cooperate with a fixed pin, an eccentric driving connection between said disc and platen, a grinding receptacle carried by said platen, means for adjustably positioning a grinding means in operative contact with said receptacle, said means including means for causing said grinding means to exert a predetermined pressure upon said receptacle, and a removable cover over said grinding means, receptacle and platen.

35 5. In a grinding and disintegrating apparatus the combination of a pedestal, a vertical shaft journaled in said pedestal, means for driving said shaft, a driving disc carried on the upper end of said shaft, a plurality of apertures eccentrically spaced in said disc, a platen movably positioned upon said disc, said platen being provided with a guide adapted to slidably cooperate with a fixed pin, an adjustable driving connection between said disc and platen, a grinding receptacle removably positioned upon said platen, means for adjustably supporting and positioning a grinding means in operative relation with said receptacle, said means including an elastic member adapted to permit said grinding means to exert a yieldable pressure upon said receptacle.

6. In a grinding and disintegrating apparatus, the combination of a driving disc, means for driving said disc, a platen movably positioned above said disc, a pin eccentrically mounted in said disc and journaled in said platen, said platen being provided with a guide adapted to slidably cooperate with a fixed pin, a grinding member carried and actuated by said platen, and a substantially stationary complementary grinding member yieldably urged into operative contact with said first named grinding member.

65 7. In a grinding and disintegrating ap-

paratus, the combination of a housing, a door in said housing, a driving disc within the housing, a platen movably positioned above said disc within the housing, a pin eccentrically mounted in said disc and journaled in said platen, said platen being provided with a guide adapted to slidably cooperate with a fixed pin, a substantially stationary grinding member, a complementary grinding member in operative contact with said first grinding member and actuated by said platen, and means positioned exteriorly of said housing and operably connected to said disc to drive the same.

Signed at Palo Alto, California, this 18th day of April, 1929.
